DESIGN FOR A HEAD FOR AN OPHTHALMOSCOPE OR THE LIKE

Charles A. Ellis, Southbridge, Mass., assignor to
American Optical Company, Southbridge,
Mass., a voluntary association of Massachusetts

Application September 11, 1944, Serial No. 115,258

Term of patent 14 years

(Cl. D57—1)

To all whom it may concern:

Be it known that I, Charles A. Ellis, a citizen of the United States of America, residing at Southbridge, in the county of Worcester and State of Massachusetts, have invented a new, original, and ornamental Design for a Head for an Ophthalmoscope or the like, of which the following is a specification, reference being made to the accompanying drawing, forming a part thereof.

Fig. 1 is a front elevational view of a head for an ophthalmoscope or the like embodying my new design;

Fig. 2 is a side elevational view of the head for an ophthalmoscope or the like as shown in Fig. 1;

Fig. 3 is a rear elevational view of the head for an ophthalmoscope or the like;

Fig. 4 is a top plan view of the head for an ophthalmoscope or the like; and

Fig. 5 is a sectional view taken on line 5—5 of Fig. 1.

The characteristic features of my design reside in the portions shown in full lines in the drawing.

I claim:

The ornamental design for a head for an ophthalmoscope or the like, substantially as shown and described.

CHARLES A. ELLIS.
